Primary Examiner — Shawn T Gingrich(74) *Attorney, Agent, or Firm* — Sturm & Fix LLC(57) **CLAIM**

The Ornamental design for a wire connector, as shown and described.

DESCRIPTION

FIG. 1 is a perspective view of a wire connector showing my new design,

FIG. 2 is a rear elevational view thereof,

FIG. 3 is a front elevational view thereof,

FIG. 4 is a top plan view thereof,

FIG. 5 is a bottom plan view thereof,

FIG. 6 is a right side elevational view thereof; and,

FIG. 7 is a left side elevational view thereof.

The broken line portion of the figure drawings is included to show portions of the wire connector that form no part of the claimed design.

1 Claim, 7 Drawing Sheets(56)
